UNITED STATES PATENT OFFICE.

THOMAS JOYSE, JR., OF SMOKELESS, PENNSYLVANIA.

FIRST-AID KIT.

Application filed February 11, 1927. Serial No. 167,538.

This invention relates to a first aid kit designed to be used with automobiles and the like, the general object of the invention being to provide a case containing gauze, bandages and the like, together with surgical instruments and medicines whereby first aid can be administered to injured and sick persons if an accident should occur or a person get sick a distance from a point where medical attention could be received.

This invention also consists in certain other features of construction and in the combination and arrangement of the several parts, to be hereinafter fully described, illustrated in the accompanying drawings and specifically pointed out in the appended claim.

In describing my invention in detail, reference will be had to the accompanying drawings wherein like characters denote like or corresponding parts throughout the several views, and in which:—

Figure 1 is a perspective view of the case in open position.

Figure 2 is a similar view with the case in closed condition.

Figure 3 is a plan view with the case in open position, with parts in section and parts broken away.

Figure 4 is a section on line 4—4 of Figure 3.

In these views, A indicates a case which is composed of the sections 1, 2 and 3. The middle section 2 is hingedly connected with the outer sections 1 and 3 by hinges 4 which are connected with the inner edges of the sections 1 and 2 and with the rear side of the section 2 an appreciable distance from the edges thereof so that the middle section will partly enter the outer sections when the case is closed. A spring latch tongue 5 on each outer section is arranged to engage a keeper recess 6 on the end of the section 2 to hold each outer section in closed position.

A partition 7 is arranged in the section 1 a slight distance from the rear side thereof so as to form a long chamber at the rear of section 1. Transverse partitions 8 are also arranged in said section and extend from the front side thereof to the partition 7 and divide the section in front of the partition 7 into a number of chambers. Each of these

chambers is provided with a lid 9 which is hinged to a partition and each lid has a spring latch tongue 10 for holding it closed. Partitions 11 may be used to divide the chambers formed by the partitions 8 into separate compartments and one of these compartments may be provided with a separate lid, as shown at 9' in the drawings, this lid being held closed by its spring latch tongue 10' which engages the partition 7. Hooks 12 are arranged in the long chamber, these hooks being mainly designed to support tourniquets in said chamber and the other chambers may be used for holding gauze, bandages, finger pads and stalls and the like.

The section 3 is also divided into a number of chambers by the partitions 13 and one of these chambers is made very large and is divided into compartments by the partitions 14, this chamber being closed by the lid 15. The compartments of this chamber may be used for holding various kinds of pins, needles, buttons and the like. One of the chambers formed by the partitions 13 is divided into a number of round chambers by the ring-shaped partitions 15 and an oblong chamber by the partition 16. These chambers are each provided with a lid 17 of the same shape as the chamber. The other chambers are closed by the lids 18, it being understood that all of the lids are provided with spring latch members. The chambers formed by the partitions 15 and 16 may be used for holding adhesive tape and the like and the chambers closed by the lids 18 can be used for holding bandages or any other article.

The section 2 is divided into two chambers by the partition 19 and this partition carries the U-shaped clamps 20 on one of its faces for supporting bottles, such as shown at 21, which may contain medicines of various kinds. Hooks 22 are fastened to the other face of the partition 19 for holding scissors, knives, tweezers and other instruments.

From the foregoing it will be seen that I have produced an inexpensive case which may be used as a first aid kit in automobiles, boats and the like, the device being compactly arranged so that it will occupy but little space in the vehicle.

It is thought from the foregoing descrip-

tion that the advantages and novel features of my invention will be readily apparent.

I desire it to be understood that I may make changes in the construction and in the combination and arrangement of the several parts, provided that such changes fall within the scope of the appended claim.

What I claim is:—

A first aid kit comprising a casing divided into three box-like sections which are hinged-
ly connected together with the outer sections overlapping the central section, partitions dividing each of the outer sections into compartments, one partition extending longitudi-

nally in one section and spaced from the hinged edge of said section, thereby forming a long narrow chamber, hooks carried by one wall of said chamber, covers for closing some of the compartments, a rigid partition in the central section intermediate the ends thereof dividing the same into two chambers, spring gripping means on one face of the partition for holding bottles and the like and means on the other face of the partition for holding instruments.

In testimony whereof I affix my signature.

THOMAS JOYSE, JR.
